The ornamental design for an electric motor controller, as shown and described.

DESCRIPTION

FIG. 1 is a top orthogonal view of my design for an electric motor controller;

FIG. 2 is a side orthogonal view of my design;

FIG. 3 is a bottom orthogonal view of my design;

FIG. 4 is an upper perspective view of my design; and,

FIG. 5 is a front orthogonal view of my design.

The broken lines shown in the view depict unclaimed environmental subject matter only and form no part of the claimed design.
